UNITED STATES PATENT OFFICE.

WILLIAM I. WOOSTER, OF HARVARD, ILLINOIS.

BLIND-FASTENER AND SLAT-OPERATOR.

SPECIFICATION forming part of Letters Patent No. 230,096, dated July 13, 1880.

Application filed February 14, 1880.

To all whom it may concern:

Be it known that I, WILLIAM I. WOOSTER, of Harvard, in the county of McHenry and State of Illinois, have invented a new and useful Improvement in House-Blinds, of which the following is a specification.

Figure 1 is a front elevation of the device, showing blind and blind-slats closed. Fig. 2 is a sectional side-elevation of the same on line 10 *x x*, Fig. 1. Fig. 3 is an elevation, partly in section, showing the blind and blind-slats open.

Similar letters of reference indicate corresponding parts.

The object of this invention is to provide improved devices for adjusting and locking the slats of blinds.

The invention consists of a slotted strip of wood or metal fixed vertically on a side of the blind and connected with each blind-slat, said strip of wood or metal being moved vertically to open or close the slats and to bolt the blind by means of a rod that passes through the window-frame; and it consists, further, of the wire device for operating the slats.

25 In the drawings, A represents a window-frame, B the blind, and C C the blind-slats.

The horizontal blind-slats C C are pivoted in the usual manner in the sides of the blind B; but instead of having a vertical strip stapled 30 to the center of each slat, as is commonly done for the purpose of adjusting said slats, I provide a strip, K, of metal or wood, having vertical slots *h h*, which strip K is movably secured to a side of the blind B by studs or screws *m*, that pass through the slots *h h* and into the blind B. The slats C C are connected to this movable strip K by the bent wires *n n*, one end of each of said wires *n* engaging in a loop or staple, *o*, in the edge of each slat C, near

the end thereof, while the other end of each of 40 said wires *n* is fixed in the edge of the strip K, so that by the up-and-down movement of the said strip K the blind-slats C are closed and locked or opened, as the case may be.

On the inner face of the blind B a bolt, L, is 45 movable vertically in staples *p*, and is moved by means of a lever, M, that is pivoted at *q*, and has one end connected with said bolt L and the other end secured in the movable strip K.

N is a rod passing horizontally partly through 50 the window-frame A, from the inner face thereof, said rod N having on its inner end a crank-handle, *r*, while the other end of said rod is bent at right angles to reach the strip K, when the blind B is closed, and engage between the 55 stops *s*, that are fixed on the face of said strip, so that when the blind B is closed the slats C C can be opened and closed and the blind itself locked and unlocked by turning the crank-handle *r*, and thereby moving the strip K up 60 or down, as may be desired.

To bolt the blind the end of the bolt L is made to enter the socket *u* in the window-sill.

Having thus described my invention, I claim as new and desire to secure by Letters Patent—

1. In a blind-slat operator, the combination, with the frame and slats, of the end-bent crank-rod N and the strip K, having stops *ss*, as shown and described.

2. The combination, with the vertical strip K and rod N, of the bolt L and lever M, substantially as shown, whereby the blind B is locked or unlocked, as set forth.

WILLIAM I. WOOSTER.
